UNITED STATES PATENT OFFICE.

ROBERT T. HAZELTON AND SOL EINSTEIN, OF CINCINNATI, OHIO, ASSIGNORS TO THE CINCINNATI MILLING MACHINE COMPANY, OF OAKLEY, CINCINNATI, OHIO, A CORPORATION OF OHIO.

AUTOMATIC MACHINE-TOOL.

1,258,614.

Specification of Letters Patent.

Patented Mar. 5, 1918.

Application filed March 15, 1915. Serial No. 14,568.

To all whom it may concern:

Be it known that we, ROBERT T. HAZELTON and SOL EINSTEIN, citizens of the United States, and residing at Cincinnati, in the county of Hamilton and State of Ohio, have invented a new and Improved Automatic Machine-Tool, of which the following application is a full disclosure.

This joint invention deals with machine tools and it undertakes to improve certain motion transmitting and controlling features thereof so as to reduce the number of parts required for the general organization and in other respects it materially simplifies the general arrangement.

Among various other objects, this joint invention contemplates a more accessible control for regulating the direction and rotation of the spindle.

Another object is to render available a system of gearing extending from the prime mover to the spindle and constructed in accordance with a speed ratio system of such a nature as will greatly promote the facility with which the various gears may be shifted and which will render it unnecessary to use gears as heavy and as large as those heretofore employed.

Another object within the contemplation of this invention is to simplify the main power control for the machine so that by the use of non-complicated elements, the power may be disconnected by a simple movement of a hand lever and a braking effect secured by a continuation of the swing of the hand lever so that the moving parts may be brought quickly to a stop.

Another object is to devise an improved junction for the spindle actuated transmission and the table-propelling transmission which may effect a reversal in the direction of the movement of the former and which, taken as a whole will represent a material saving in the number of parts required in accomplishing these functions.

Another object is to provide a relation between the table control and the oil pump or table feed so that the number of elements required to constitute the transmission will be reduced.

Another object is to create a simplified control for the spindle speeds whereby by moving a single lever progressively into successive positions, the spindle speeds may be correspondingly varied.

Other objects will be in part obvious from the annexed drawings and in part indicated in connection therewith by the following analysis of this invention.

This invention accordingly consists in the features of construction, combinations of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Fig. 1 is a diagrammatic drawing depicting a gear arrangement such as is herein proposed for giving the spindles a series of speeds, for changing the direction of rotation thereof, and for providing the speed ratios enabling a general simplification to be effected.

Fig. 2 is a horizontal section taken through line 2, 2, of Fig. 4 through the speed change box showing the arrangement of certain control elements whereby a single handle may yield four speed ratios.

Fig. 3 is a fragmentary side elevation partly in section taken through line 3, 3, of Fig. 4 of the hand lever and the gear shifting arms.

Fig. 4 is a side elevation of the speed change box.

Fig. 5 is a section through line 5, 5, of Fig. 4 showing further details.

Fig. 6 is an isolated partial assembly of the gear actuating lever system arranged in a single plane to better show the arrangement of the parts.

Fig. 7 is a side elevation of a milling machine of a knee-column type exemplifying how any species of milling machines may be reorganized to embody this joint invention.

To obtain an adequate understanding of this invention, it should be kept in mind that the term "feed", as used herein, indicates any one of a series of relatively slow movements of the table all essentially suitable for tooling operations, and the term

"feed-changer" or "feed-change mechanism" indicates only that particular device which determines the rate at which the table thus "feeds"; and it is to be distinguished from 5 variable speed devices which effect changes not all identified with a tooling operation, as well as from the "speed-change mechanism" herein referred to and which determines the speed of rotation of the cutter 10 spindle.

Before detailing the specific features of construction whereby these functions are attained it will be convenient first to describe certain major elements of a conventional 15 milling machine. These comprise a table Y that supports the work and which is reciprocated to-and-fro to subject the work bolted thereon to the effect of the tool or cutter that is secured to an appropriate tool-supporting 20 member here typified by a spindle X which, in this instance, is continuously rotated by power derived from the same source or prime-mover that actuates the table. In order to enable the machine properly to execute its functions, these actuated elements 25 must be capable of being brought into adjustable relation with one another in two directions. This is accomplished by an interponent frame-unit B that intervenes between the frame-unit A that directly supports the spindle or tool-supporting member 30 and the frame-unit C that directly mounts the table. In the type of machine illustrated, the interponent frame-unit B is commonly termed a "knee," the table-supporting frame-unit C is usually termed a "saddle," and the spindle mounting frame-unit A is generally termed a "column." The chief 35 mechanical characteristic of the interponent frame-unit B is that it provides for a relative vertical adjustment as to the spindle-mounting unit, and a horizontal adjustment as to the table-supporting unit, *i. e.*, in a direction transverse to the other.

40 The spindle-mounting frame-unit, or "column" A, has heretofore been that also selected to rest on the floor and thus provide a foundation for the machine, as a whole, and it has also been utilized to support or 45 mount both the change-gear mechanism that varies the speed of the spindle, as well as the change-gear mechanism that varies the rate of feed of the table. This, however, has resulted in a very considerable inconvenience to the attendant in manipulating the machine. That is to say, the attendant must be stationed at the outer longitudinal side of the reciprocating table in order to scrutinize the action of the machine, but, 50 when so stationed, he is out of reach of the levers that effect all the changes of the rate of feed of the table, so that, in order to make these changes he must shift his position. U. S. Patent No. 1,125,686 proposes, among 55 other things, a rearrangement and a recon-

struction of the control elements so as to free the so-called "column" of the machine from the mechanism that governs the rate at which the table shall feed, and so to locate the said mechanism, and so to combine it 70 with other control features that the attendant, when stationed at the outer longitudinal edge of the reciprocating table (the edge remote from the frame-unit that uprises across the plane of the table) and without 75 shifting his position, will be able, first, to change the rate at which the table feeds, *i. e.*, to vary its speed during a cutting stroke; second, to change the direction of travel of the table, either manually or automatically; 80 and third, to stop the movement of the table either manually or automatically. In carrying out this aspect of said invention, one of the frame-units carrying the weight of the table may assume any conventional proportions or configuration, such as are indicated on the drawings, but with this distinction, that it is contrived also to support or carry the weight of what may be termed a "feed-change" box, *i. e.*, the casing and elements constituting a change-gear mechanism 85 such that the rate of "feed" may be varied at will. This box may also include other control features, such as the means for determining the direction of movement of the 90 table; all for example as fully set forth in said patent.

A more comprehensive grasp of the various aspects of this invention may perhaps be obtained by tracing the course of motion 100 through the machine in connection with a description of the structural features involved.

At a convenient point, as for example on a column A, is mounted a prime mover P, 105 here instanced as a pulley, and both the spindle and the table may be driven by this prime mover.

In the embodiment under description, the table-feed transmission system derives motion directly from the prime-mover and includes the beveled gear 1 secured to the shaft p^1 and meshing with a beveled gear 2 which is located at the upper end of a shaft 3 which depends alongside of the frame-unit 110 A or "column" and enters a box at the side of said frame-unit; within which it terminates in a bevel 4 that meshes with the bevel 5 secured to the horizontal knuckle 6. The foregoing embodiment constitutes a very 115 simple structure for so locating the knuckle 6 that the deflection necessary for shaft 7 will be reduced to a minimum. The motion is then transmitted through the feed-change box C¹ to actuate the table Y in any desired 120 manner.

The spindle-propelling transmission, including the gearing enabling the rate of speed to be varied, will now be described. In this embodiment, this transmission ex- 130

tends from the initial terminal-member d^2 to the ultimate terminal-member x , which in this instance is not shiftable. This transmission derives motion from the prime mover P preferably through a motion reverser so that the spindle may be caused to rotate in either direction. To that end, this invention provides a combination junction and reversing device whereby the parts are reduced in number and a much simpler arrangement is thereby afforded. This device comprises two opposite coaxial bevel gears 1 and d^1 each of which permanently meshes with an intervening bevel gear 2 having its axis arranged transversely to the other gears. The bevel 1 is keyed to shaft p^1 and is driven by the pulley P ; the bevel 2 is keyed to the table-feeding or pump-driving shaft 3; and the bevel d^1 idles about the shaft d^3 and turns contrary to bevel 1. This pump-driving and table-feeding shaft 3 terminates at its lower end in a bevel gear 4 which is coaxially opposite to another bevel gear 2 which is keyed to the upper end of the shaft b which is connected at its lower end to a pump c so as to drive it. An intermediate bevel gear 5 meshes simultaneously with both gears 4 and 2 and is connected to a knuckle 6 whereby the extensible shaft 7 is driven. By means of this arrangement, the pump driving mechanism bears a simplified relation to the table mechanism. A double-ended clutch d^2 is splined to shaft d^3 and is shifted to clutch either bevel 1 or bevel d^1 to said shaft by means of lever d shown in Fig. 7; thereby enabling the direction of the spindle to be reversed without affecting the direction of rotation of the table-feeding transmission. Shiftably mounted on the shaft d^3 are two independently movable units or gear-bearers d^4 and d^5 . The former carries the gears d^6 and d^8 , and the latter carries the gears d^7 and d^9 , and the purpose of enabling these gear bearers to be shifted is to utilize one or another of said four gears for propelling or transmitting purposes. Keyed to a shaft D^1 journaled in parallelism with shaft d^3 is a series of gears D^6 , D^7 , D^8 , D^9 which is so arranged that gear d^6 may be brought into mesh with gear D^6 , and so on. In a suitable manner, motion is derived from any one of these four gears. Thus, the shaft g^1 carries a gear g^{10} which may be brought into mesh with gear D^{10} (keyed to shaft D^1) by a lateral movement of the unit g^4 , or similarly the gear g^9 may be meshed with gear D^9 . These gears are shifted by the arm g . Inasmuch as the unit g^2 is splined to the shaft g^1 , the latter will be rotated at a rate dependent upon the character of the foregoing intermeshing; with the effect that gear g^2 , which is fast to the shaft g^1 , will directly drive the gear G^2 and indirectly the gear G^3 at a corresponding rate.

The gears G^2 and G^3 are constructed together preferably to form a single shifting gear unit which is mounted on a shaft G^1 and is adapted to be shifted by means of a lever G having an arm G^4 terminating in a shoe seated within the angular groove G^5 .

The gear g^2 is elongated so that it may constantly mesh with the gear G^2 in all positions of the latter. A gear unit x is keyed to the spindle X and provides a large gear x^3 adapted to mesh with the pinion G^3 and the gear unit x also provides a pinion x^2 adapted to be brought into mesh with the large gear G^2 . In consequence of this arrangement sixteen different spindle speeds 75 become available as follows: Four closely graduated speeds by means of the single hand lever D ; these doubled by means of the hand lever g having an arm g^3 shifting the gear unit g^4 ; and these eight speeds again 80 doubled by means of the hand lever G above described.

A unique characteristic of this gear series lies in the peculiar relationships and the rates of the said speeds. By turning to Fig. 90 1, it will be perceived that the four closely graduated speeds are obtained by shifting gear units which are comparatively small in diameter and which rotate at a very high speed by virtue of being connected to receive 95 undiminished the full speed of the prime-mover. Between this speed-changer and the spindle is a reducing pinion g^2 which enables the pulley to run at a proportionately high speed and reduces the strain on the 100 gears and the pressures on the various shafts. It has been found, contrary to the prevailing belief, that at the high speeds at which the gear units d^4 and d^5 run, the shifting 105 can be effected with much less clashing of teeth.

For the purpose of giving a better control to the main power supply of the machine, the prime mover P has a loose mounting 110 about the shaft p^1 , and is adapted to be connected therewith by means of a clutch member p^2 which is splined to said shaft, and which in turn is positioned by means of an elongated rod p^3 extending through shaft p^1 and shaft d^3 , and which has its other extreme end pinned to a friction brake p^4 having a beveled face adapted to cramp against a counterpart face on a stationary element p^5 . This arrangement locates the control of 115 the main power relatively near the front of the machine, and the shifting is effected by an elongated lever P^2 adapted to be connected at various angles with the shaft P^3 by means of clutch teeth, as shown in Fig. 4. The lower end of this shaft carries an arm 120 p^5 which has its extremity seated in a groove p^6 in a clutch p^4 so that by swinging the large lever P^2 , the power may be disconnected and a brake p^4 p^5 applied.

The hand-operating mechanism for ena- 130

bling the attendant to shift the four coaxial gears of the speed-change mechanism so that the spindle may be caused to rotate at any one of the selectively available speeds, 5 may now be described. This mechanism embodies certain improvements simplifying its construction and also enhancing its facility of operation. In this embodiment, a single hand lever D is utilized to control the 10 four feed-changes constituting what may be termed the first and second series of multipliers. This lever, is indicated by the character D on Figs. 2 to 7, and it comprises an arm or shank 50 that extends through a 15 cross-slot (see Fig. 2) in a positioning or guard-plate 51 that projects laterally from the side of the gear-box A¹ which contains the speed-change mechanism as aforesaid. This brings the grip of the lever D adjacent 20 the side of the column, where it will at all times be within the convenient reach of the attendant. The other end of the lever is flattened to form a gear-segment 52 which is received by a radial slot 53 provided in the 25 end-portion 54 of an elongated sleeve 55 which extends transversely to the hand-lever D and is journaled in the gear-box A¹ so as to permit of rotation, but not of an axial movement. The other end of this 30 sleeve 55 provides an offset arm 56 terminating in a shoe 57 that rides in the circumferential groove 58 of the gear unit d⁶ so that when the sleeve 55 is partially rotated by moving the hand-lever D right or 35 left, the gear-unit d⁶ will be shifted axially so as to cause one of its gears to mesh with another gear, and so that, when the hand-lever is in an intermediate position, the gear-unit d⁶ will also be in an intermediate or 40 non-transmitting position. In the arrangement shown, when the hand lever D is in its left position, the gear-unit d⁶ will be shifted to the left, as seen by Figs. 3 and 6, with the effect that gear d⁹ will mesh with gear D⁹. 45 This is the position indicated by "d⁹ D⁹" on Fig. 2. So also when the hand-lever is in its right position (d⁷ D⁷), the gear d⁷ will mesh with the gear D⁷. Thus the lateral movement of the hand lever D will determine 50 the position of the gear-unit d⁶. The construction is such, moreover, that the transverse movements of the hand lever D will also control the position of the gear-unit d⁴. A pin 59 pivots the hand lever to a radial 55 extension 60 of the sleeve 55 and a rod 61 extends coaxially through the bore of the sleeve 55 and it provides a rack 62 meshing with the teeth of the gear-segment 52 so that transverse oscillations of the hand lever D 60 will reciprocate the rod 61 and, by means of another rack 63, this reciprocating motion is utilized to oscillate a lever 64 which is pivoted at 65, and has an arm 66 terminating in a gear-segment meshing with the rack 63. 65 The sleeve 55 has one side cut away, as indi-

cated by the slot W, so that the arm 66 may mesh with the rack 63 without interfering with the turning of the rock-sleeve 55. This lever 64 also meshes with a part D¹¹ pivoted at D¹² and having an arm which terminates 70 in a shoe 67 riding in a circular groove 68 of the gear-unit d⁴ so as to control the positions thereof. Hence, when the hand lever D is swung to the position d⁸ D⁸ indicated by Fig. 3, the gear d⁶ will be brought into 75 mesh with the gear D⁸ and conversely, when it is swung into the position d⁷ D⁷ the gear d⁷ will mesh with the gear D⁷. The relation of these various gears d⁶, d⁷, d⁸ and d⁹ to the transmission system is such that but one of 80 them may be operating at the same time, otherwise something would have to break and this circumstance is precluded by the use of the cross-slot in the plate 51. In order that the hand lever D may remain in 85 any one of its various positions, ball-pawl 69 and 70 will preferably be provided to operate with the appropriate recesses in the lever D¹¹ and the sleeve 55, respectively, as will be understood by referring to Fig. 2. 90

Having thus revealed this invention, we claim as new and desire to secure the following combinations of elements and equivalents thereof by Letters Patent of the United States:—

1. A machine - tool organization combining a tool-support; a work-support; a first bevel-gear; a second power-driven bevel-gear coaxial with said first bevel-gear; a shiftable clutch adapted to operatively connect either one of said bevel-gears in propelling relation with one of said supports; a third bevel-gear meshing with each of said other bevel-gears; and means establishing a propelling relation between said 105 third bevel and the work support.

2. A machine - tool organization combining a gear-set adapted to yield a plurality of speeds; a guide-plate providing a similar number of slots radiating from a common center; a lever adapted to be shifted through the common center into each of said slots; and mechanism adapted to adjust said gear-set to yield successively greater speeds as said lever is shifted successively from the one slot into the immediately adjacent slot.

3. A machine - tool organization combining a prime-mover; a spindle; a tubular shaft; a shiftable gear on said shaft; means enabling said prime-mover to drive said spindle through the agency of said gear; means impeding the free rotation of said gear and comprising an element in telescopic relation with said tubular shaft and 125 a hand lever for shifting said element axially with relation to said tubular shaft to enable said prime mover to rotate said shaft and gear.

4. A machine - tool organization combin- 130

ing a work-support table; a prime-mover; a shaft extending downwardly therefrom; a pump; a shaft extending upwardly therefrom; a bevel-gear at the end of each shaft; 5 a third bevel-gear meshing with each of the other two; a table; a shaft extending laterally from said third gear and operatively connected to said table and a flexible joint connecting said shaft with said third gear 10 to permit the vertical swing of said shaft to accommodate the rise and fall of said table.

5. A milling-machine combining two co-axially arranged tubular-shafts; a bevel- 15 gear fixed to one shaft; a second bevel-gear free from the other shaft; a clutch splined to said last-mentioned shaft; a third bevel- gear meshing with said two gears; a prime- mover; a rod extending through said shafts; 20 rod-operated means for establishing a driving relation between said prime-mover and one of said shafts; a spindle; and gearing for transmitting motion from one of said shafts to said spindle.

25 6. A milling-machine combining two co-axially arranged tubular-shafts; a bevel- gear fixed to one shaft; a second bevel-gear free from the other shaft; a clutch splined to said last-mentioned shaft; a third bevel- 30 gear meshing with said two gears; a vertical shaft extending downwardly from said shaft extending downwardly from said third bevel-gear; a work-support actuated by said vertical shaft; a prime-mover; a rod extending through said shafts; rod-oper- 35 ated means for establishing a driving relation between said prime-mover and one of said shafts; a spindle; and gearing for

transmitting motion from one of said shafts to said spindle.

7. A milling-machine combining a spin- 40 dle; a non-translatable cone of gears thereon; an intermediate shaft; a cone of gears translatable thereon to engage successively the spindle gears; an intermediate axle; transmission gears non-translatable carried 45 by said axle; a power-driven shaft; gears translatable mounted thereon to be engaged with said transmission gears; and a shift- able cone of gears adapted to be translated to selectively engage one of said transmission gears to enable the latter to propel the gears on the first-mentioned intermediate shaft.

8. A milling-machine combining a spin- 55 dle; a power-driven arbor; a first shaft near the spindle; a second shaft near the arbor; a first and second set of gears non- translatable mounted on the spindle and second shaft, respectively; a first and a sec- 60 ond set of gears shiftably mounted on the first shaft and arbor respectively; and an intermediate set of gears adapted to be translated to selectively enable said first set of shiftable gears to be driven by the second set of non-translatable gears. 65

In witness whereof, we hereunto subscribe our names as attested by the two subscribing witnesses.
